UNITED STATES PATENT OFFICE.

WILLIAM H. HARRISON, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,330,467.

Specification of Letters Patent. Patented Feb. 10, 1920.

Application filed April 11, 1918. Serial No. 227,916.

To all whom it may concern:

Be it known that I, WILLIAM H. HARRISON, a citizen of the United States, residing at Brooklyn, in the county of Kings, State 5 of New York, have invented certain new and useful Improvements in Telephone-Exchange Systems, of which the following is a full, clear, concise, and exact description.

This invention relates to telephone exchange systems, and more particularly to such systems of the central energy type.

The object of this invention is to provide improved means for controlling the association of an operator's telephone set 15 with the link circuits employed for inter-connecting telephone lines.

In accordance with one feature of this invention an operator's position is provided with means responsive to the actuation of 20 the listening switch of the link circuit, when one of the two supervisory relays thereof is energized and the other is deenergized, thereby to connect the operator's telephone set with the link circuit.

For a more complete understanding of this invention, reference should be had to the following description considered in connection with the accompanying drawings, in which Figures 1, 2 and 3, when placed end 30 to end in the order named, illustrate one embodiment of the present invention.

Referring to the drawings, there is shown a two-way trunk circuit C extending from the originating or information operator's desk or position X to a chief operator's desk Y. A cord circuit B provided at the information operator's desk X may be employed to connect the information operator's telephone set with the trunk circuit C. A two- 40 way trunk circuit E extends from the chief operator's desk Y to the manager's or assistant manager's desk Z. A link circuit D provided at the chief operator's desk Y may be employed in answering calls incoming 45 over either trunk circuit, in initiating calls outgoing over either trunk circuit, or in completing connections between the information desk X and the manager's desk Z. The trunk circuit C terminates in a key or 50 switch at the manager's desk, by the actuation of which calls may be answered or initiated. It will be understood of course that the jack-ended trunk circuits may be and usually are provided with multiple 55 jacks. The single jacks are shown merely

for convenience. These trunk circuits may very properly be considered as telephone lines which terminate at the chief operator's desk Y. It will be understood too, that a plurality of trunk circuits similar to C and E may be employed, only one of each being shown merely for convenience. The apparatus shown to the left of the dotted line 4-4 is associated with the originating or information operator's position or desk X, that shown between the dotted lines 4-4 and 5-5 with the chief operator's desk Y, and that shown to the right of the dotted line 5-5 with the manager's or assistant manager's desk Z. In Fig. 2, the apparatus shown above the dotted line is common to a plurality of link circuits.

With this brief description of the drawings in mind, it is thought that the invention will be fully understood from a description of the operation of the system disclosed therein.

The information operator X desiring to communicate with the chief operator Y actuates listening key 6 and inserts plug 7 of cord circuit B into jack 8 of the trunk circuit C, thereby causing the operation of relay 10 over a circuit from battery through resistance 11, sleeve contacts of the plug 7 and the jack 8 and the winding of the relay 10 to ground. Relay 10 in operating causes lamp 13 to be lighted over a circuit from battery through the upper contact of relay 10, upper contact of relay 9 and the lamp 13 to ground. Relay 12 is energized 85 by the operation of relay 10 to open the circuit of and prevent the lighting of lamp 21 when the chief operator answers. The lighting of the lamp 13 serves as a line signal to the chief operator. The operation of relay 10 also connects battery and ground to the ring and tip conductors respectively of the chief operator's desk end of the trunk circuit C for purposes of supervision.

The chief operator, observing the lighted condition of the lamp 13, inserts answering plug 15 of the cord circuit D into jack 16 of the trunk circuit C, whereupon relay 14 operates over a circuit from battery through resistance 17, contact 18 of listening key 19, sleeve contacts of the plug 15 and the jack 16 and the winding of relay 14 to ground. Relay 14, in operating, connects battery and ground to the ring and tip conductors respectively of the information desk end of 110

the trunk circuit C, and causes the operation of relay 9. Relay 9, in operating, opens the circuit of and extinguishes the lamp 13. Relay 12 is now locked up over a circuit from 5 battery through the winding and lower contact thereof and the lower contact of relay 14 to ground. The locking up of relay 12 under control of relay 14 prevents the lighting of the lamp 21 upon the disconnection 10 of the cord circuit B from the trunk circuit C, before the cord circuit D is disconnected therefrom. Likewise when relay 9 operates it is locked up through a contact of relay 10, so that the lamp 13 cannot light should 15 the cord circuit D be disconnected before the cord circuit B. Both relays 9 and 12 remain locked up until both cord circuits have been disconnected. The insertion of the plug 20 into the jack 16 also causes the operation of supervisory relay 27 of the cord circuit D over a circuit from battery through the upper contact of relay 10, ring contacts of the jack 16 and the plug 15, the winding of supervisory relay 27, contact 24 of the listening 25 key 19, retardation coil 23, tip contacts of the plug 15 and the jack 16 and the lower contact of relay 10 to ground. Supervisory relay 27, in operating, opens a contact in 30 circuit with the answering supervisory lamp 34, thereby preventing the lighting thereof when the calling end of the cord circuit D is connected with trunk circuit E.

The chief operator may now actuate listening key 19 to connect the telephone set 35 with the talking strands of the cord circuit D. Upon the actuation of the listening key 19, relay 20 operates over a circuit from battery through the winding of relay 20, contact 25 of the listening key 19, sleeve contacts of the plug 15 and the jack 16 and the winding of relay 14 to ground. Since contact 25 makes before contact 18 breaks relay 14 is not deenergized when the listening key 19 is actuated. Relay 20, in operating 40 opens a contact in circuit with busy test relay 47, thereby disconnecting this busy test relay from the tip or testing conductor associated with the answering end of the cord circuit. Upon the actuation of the listening key 19 the windings of retardation coil 31 45 and relay 28 are connected in bridge of the talking conductors of the cord circuit D in substitution of the winding of the retardation coil 23. Supervisory relay 27 remains 50 operated, and relay 28 operates. The operating circuit for relay 28 may be traced from battery through the upper contact of relay 10, ring contacts of the jack 16 and the plug 15, winding of supervisory relay 55 27, contact 29 of listening key 19, lower normal contact of ringing key 30, winding of relay 28 and lower winding of retardation coil 31 in parallel, upper winding of retardation coil 31, upper normal contact of ringing key 30, contact 32 of listening key 19, 60

tip contacts of the plug 15 and the jack 16 and the lower contact of relay 10 to ground. Relay 28, in operating, establishes energizing circuits for a fast-operating and slow-releasing relay 40 and a slow-operating relay 41. The energizing circuit for relay 40 is from battery through the winding of relay 40, normal contact of relay 41, left-hand normal contact of relay 42 and contact of relay 28 to ground, while the energizing circuit for relay 41 is from battery through the winding of relay 41, left-hand normal contact of relay 42 and the contact of relay 28 to ground. Fast-operating relay 40, in attracting its armature, opens its contact, 70 which is in the energizing circuit of relay 42. Slow-operating relay 41, upon attracting its armatures, opens the circuit of relay 40, and closes a contact in the energizing circuit of relay 42, so that upon the release of the 75 slow-releasing relay 40, relay 42 is operated over a circuit from a battery through the winding of relay 42, contact of relay 40, and left-hand contact of relay 41 to ground. Relay 42, in operating, closes its left-hand 80 alternate contact, thereby establishing a locking circuit for itself through the contact of relay 28 to ground. The opening of the left-hand normal contact of relay 42 releases relay 41. Relays 40 and 41 cannot 85 be energized again until after the release of relay 42. Relay 42, in operating, also closes its right-hand and middle alternate contacts, thereby connecting the operator's telephone set with the talking strands of the cord circuit D. The chief operator is now connected 90 with the information operator.

While the delay in the connection of the operator's telephone set with the talking circuit is of no particular value when answering a call over a trunk circuit to the outgoing end of which is connected a link circuit not equipped for automatic ringing, still it is of considerable value when answering a call over a trunk circuit to the 105 outgoing end of which is connected a link circuit equipped for automatic ringing, in which case the usual severe clicks in the receiver, due to the disconnection of the ringing current, are avoided.

The chief operator may now converse with the information operator to whom information as desired may be furnished. If the chief operator is not able to furnish all of the information desired or should the information operator wish to converse with the manager, the chief operator restores the listening key 19 to normal position and inserts plug 43 of the cord circuit D into jack 44 of the trunk circuit E. Upon the restoration of the listening key 19, relays 20, 28 and 42 release, while the insertion of the plug 43 into the jack 44 causes the operation of relays 45 and 50 over a circuit from battery through the winding of relay 45, 110 120 125 130

sleeve contacts of the plug 43 and the jack 44 and the winding of relay 50 to ground. Relay 45, in operating, disconnects the busy test relay 47 from the tip or test conductor 5 of the calling plug 43, closes a contact in the tip strand of the cord circuit D, and causes the lighting of calling supervisory lamp 48 over a circuit from battery through the lamp 48, normal contact of calling supervisory relay 49 and lower alternate contact 10 of relay 45 to ground. Relay 50, in operating, lights a lamp 51 at the manager's desk over a circuit from battery through the upper contact of relay 50, the upper contact of relay 52 and the lamp 51 to ground. Relay 50 in operating also causes the energization 15 of relay 53 which opens its upper contact in circuit with a lamp 54, to prevent the lighting thereof when the manager answers. The manager observing the lighted condition 20 of the lamp 51 actuates listening key 55, whereupon relays 56 and 57 operate in parallel over a circuit which includes the lower contact of the listening key 55. Relay 56, in operating, causes the operation of relay 52 over a circuit from battery through the winding of relay 52 and the upper contact 25 of relay 56 to ground. The operation of relay 52 opens the circuit of and extinguishes the lamp 51. Relays 52 and 53 remain locked up until the plug 43 is withdrawn from the jack 44 and the listening key 55 is restored to normal position. Relay 56, in operating, also connects talking 30 battery to the trunk circuit E and causes the operation of calling supervisory relay 49 over a circuit from battery through the lower contact of relay 56, repeating coil winding 60, ring contacts of the jack 44 and the plug 43, the winding of the calling supervisory relay 49, repeating coil winding 61, resistance 62, repeating coil winding 63, upper alternate contact of relay 45, tip contacts of the plug 43 and the jack 44, 35 repeating coil winding 64 and the upper contact of relay 56 to ground. Calling supervisory relay 49 in operating opens the circuit of and extinguishes the calling supervisory lamp 48, which indicates to the chief operator that the manager has answered. Since the operation of relay 57 connected 40 the manager's telephone set with the trunk circuit E, the manager may now converse with the information operator. At the conclusion of the conversation between the information operator and the manager, the information operator withdraws the plug 7 from the jack 8 and the manager restores the listening key 55 to 45 normal position. The withdrawal of the plug 7 from the jack 8 causes the release of relay 10, which disconnects battery and ground from the chief operator's desk end of the trunk circuit C, whereupon answering supervisory relay 27 of the cord circuit D 50 is deenergized to light the answering supervisory lamp 34 over a circuit from battery through the lamp 34, contact of relay 27 and lower contact of relay 45 to ground. The restoration of the listening key 55 to 55 normal position causes the deenergization of relays 56 and 57. The deenergization of relay 56 disconnects battery and ground from the chief operator's desk end of the trunk circuit E, whereupon the calling supervisory 60 relay 49 of the cord circuit D releases. The release of relay 49 causes the calling supervisory lamp 48 to be lighted. The lighting of the two supervisory lamps 34 and 48 serves as a disconnect signal 65 to the chief operator who may withdraw the plugs from the jacks, restoring all apparatus to normal condition. Should the manager, at the conclusion of the conversation with the information operator and before the chief operator has withdrawn the plug 43 from the jack 44, wish to converse with the chief operator, the listening key 55 is repeatedly actuated to open 70 and close its contacts, thereby to cause the intermittent lighting of the calling supervisory lamp 48 which serves as a signal to the chief operator. After so actuating the listening key 55 in this manner, the manager leaves the key actuated so that the relays 56, 57 and 49 are operated. Since the information operator has already withdrawn 75 the plug 7 from the jack 8, answering supervisory relay 27 is deenergized so that relay 65 is now energized over a circuit from battery through the lamp 48, alternate contact of relay 49, the winding of relay 65, contact of relay 27 and lower alternate contact of relay 45 to ground. The lamp 48 is not 80 lighted over this circuit, but the answering supervisory lamp 34 remains lighted. The chief operator, having noted the intermittent lighting of the calling supervisory lamp 48 while the answering supervisory lamp 34 is continuously lighted, recognizes 85 this as a signal that the manager is signaling, and actuates the listening key 19. Upon the actuation of this listening key, energizing circuits are established for the quick-operating and slow-release relay 40 and the slow-operating relay 41, which may be 90 traced from battery through the windings of these relays in parallel, left-hand normal contact of relay 42, contact 66 of listening key 19 and the contact of relay 65 to ground. Relays 40 and 41 function as before described to delay the energization of relay 42 which in operating connects the chief operator's telephone set with the cord circuit D and locks up through its left-hand alternate 95 contact, contact 66 of listening key 19 and the contact of relay 65 to ground. The chief operator's telephone set will remain connected to the cord circuit until the listening key 19 is restored to normal position, 100

the plug 43 is withdrawn from the jack 44, or the manager restores the listening key 55 to normal position.

Should the chief operator initiate a call by employing the answering plug 15, the trunk circuit is tested before the plug is inserted in the jack. In making this busy test, the operator actuates the listening key 19 and then touches the tip of the plug 15 against the sleeve terminal of the jack if the trunk is busy, the busy test relay 47 operates over a circuit from battery at the test terminal of the jack, tip of the plug 15, contacts 32 and 67 of the listening key 19, right-hand normal contact of relay 42, contact of relay 20 and the winding of the busy test relay 47. Busy test relay 47 in operating connects battery in circuit with the primary winding of induction coil 68, whereupon a click is produced in the receiver of the operator's telephone set.

What is claimed is:

1. A telephone exchange system comprising two telephone lines, a link circuit interconnecting the lines, a supervisory signal control relay for each end of the link circuit, an operator's telephone set, a listening key, a third relay energized only when one of the supervisory relays is energized and the other 25 is deenergized, and a fourth relay responsive to the actuation of the listening key while the third relay is energized to connect the operator's telephone set with the link circuit.

2. A telephone exchange system comprising two telephone lines, a link circuit interconnecting the lines, a supervisory signal control relay for each end of the link circuit, an operator's telephone set, a listening key, a third relay, an energizing circuit therefor including a contact of one supervisory relay when energized and a contact of the other supervisory relay when deenergized, and a fourth relay responsive to the 40 actuation of the listening key while the third relay is energized to connect the operator's telephone set with the link circuit.

3. A telephone exchange system comprising two telephone lines, a link circuit interconnecting the lines, a supervisory signal 50 control relay for each end of the link circuit, a listening key, a third relay energized when one of the supervisory relays is energized and the other is deenergized, a fourth relay, an energizing circuit therefor established while the listening key is actuated and the third relay is energized, and an operator's telephone set connected with the link circuit through contacts of the fourth relay and the listening key.

60 4. A telephone exchange system comprising two telephone lines, a link circuit interconnecting the lines, a supervisory signal control relay for each end of the link circuit, an operator's telephone set, a listening key, a 65 third relay whose energization depends upon

the energized condition of one supervisory relay and the deenergized condition of the other supervisory relay, a fourth relay for connecting the operator's telephone set with the link circuit, and an energizing circuit 70 therefor including contacts of the actuated listening key and the energized third relay.

5. A telephone exchange system comprising two telephone lines, a link circuit interconnecting the lines, a supervisory signal control relay for each end of the link circuit, an operator's telephone set, a listening key, a third relay, an energizing circuit 75 therefor completed through a contact of one supervisory relay while energized and 80 a contact of the other supervisory relay while deenergized, a fourth relay for connecting the operator's telephone set with the link circuit, and an energizing circuit therefor including contacts of the actuated 85 listening key and the actuated third relay.

6. A telephone exchange system comprising a plurality of telephone lines terminating in an operator's position, a plurality of link circuits thereat, one of which interconnects two of the lines, a supervisory signal control relay for each end of the engaged link circuit, an operator's telephone set, a listening switch, a relay common to the link circuits of the operator's position for connecting the operator's telephone set with the engaged link circuit, and an energizing circuit for the common relay whose completion depends upon the actuation of the 95 listening switch, the energized condition of one supervisory and the deenergized condition of the other supervisory relay.

7. A telephone exchange system comprising two telephone lines, a link circuit connected with one of the lines, a relay in the 105 link circuit controlled over the connected line, a local circuit relay energized upon the connection of the link circuit with the other telephone line, a relay in the link circuit controlled over the second connected line, 110 an operator's telephone set, a listening key for the link circuit, a fourth relay in the link circuit whose energization depends upon the energized condition of the local circuit and second line controlled relays and 115 the deenergized condition of the first line controlled relay, and means responsive to the actuation of the listening key while the fourth relay is energized to connect the operator's telephone set with the link circuit.

8. A telephone exchange system comprising two telephone lines, a link circuit connected with one of the lines, a relay in the link circuit controlled over the connected line, a local circuit relay energized 125 upon the connection of the link circuit with the other telephone line, a relay in the link circuit controlled over the second connected line, an operator's telephone set, a listening key for the link circuit, a fourth relay in 130

the link circuit, an energizing circuit therefor including a contact of the local circuit relay, a contact of each line controlled relay, and means responsive to the actuation 5 of the listening key while the fourth relay is energized to connect the operator's telephone set with the link circuit.

9. A telephone exchange system comprising two telephone lines, a link circuit connected with one of the lines, a relay 10 in the link circuit controlled over the connected line, a local circuit relay energized upon the connection of the link circuit with the other telephone line, a relay in the link circuit controlled over the second connected line, an operator's telephone set, a listening key for the link circuit, a fourth relay in the link circuit whose energization depends upon the energized condition of 15 the local circuit and second line controlled relay and the deenergized condition of the first line controlled relay, and a relay energized upon the actuation of the listening key while the fourth relay is energized to connect the operator's telephone 20 set with the link circuit.

10. A telephone exchange system comprising two telephone lines, a link circuit connected with one of the lines, a relay in the link circuit controlled over the connected line, a local circuit relay energized upon the connection of the link circuit with the other telephone line, a relay in the link circuit 25

circuit controlled over the second connected line, an operator's telephone set, a listening 35 key for the link circuit, a fourth relay in the link circuit energized only while the local circuit relay and the second line controlled relay are energized, and the first line controlled relay is deenergized, a relay 40 for connecting the operator's telephone set with the link circuit, and an energizing circuit therefor controlled by the listening key and the fourth relay.

11. A telephone exchange system comprising a plurality of telephone lines terminating at an operator's position, a plurality of link circuits thereat, one of the link circuits interconnecting two of the telephone lines, supervisory relays for the 45 engaged link circuit, signaling devices controlled by the supervisory relays, a third relay in the engaged link circuit, an energizing circuit therefor controlled by the supervisory relays, a listening key for the 50 engaged link circuit, a relay common to the link circuits, an energizing circuit for the common relay controlled by the listening switch and the third relay, and an operator's telephone set connected with the link 55 circuit through contacts of the common relay and the listening switch.

In witness whereof, I hereunto subscribe my name this 5th day of April A. D., 1918.

WILLIAM H. HARRISON.
